ROLLED COLLAR STAY

Ernest Heuman, West End, N. J.

Application November 30, 1951, Serial No. 259,265

2 Claims. (Cl. 2—132)

1

The present invention relates to new and useful improvements in collar stays.

More specifically, the present invention proposes the construction of collar stays for being invisibly mounted on the wings of a conventionally constructed man's shirt or the like garment in a manner to hold the wings in a slight forwardly projected curvature and retain the tip ends of the wings from curling upward.

Another object of the present invention proposes constructing the collar stays as light weight bodies shaped to conform to the triangular formation of the wings of the collar and which are given a slight preset curvature from top to bottom so as to impart a similar curvature to the wings of the collar.

Still further, the present invention proposes mounting the bodies on the wings with their convex sides faced outward so that the wings of the collar will be held in a slight forwardly curved position with the tips of the wings directed inward.

As a further object, the present invention proposes forming the bodies of an inert material as one of the synthetic resinous materials so that the bodies may be sewn directly into the wings of the collar to be laundered with the shirt without harmful effect on the collar of the shirt.

The present invention further proposes forming the light weight bodies in outline shape to reduce the bulk thereof.

Still another object of the present invention proposes several different methods for reinforcing the bodies so as to maintain them in the desired preset curvature.

It is a further object of the present invention to construct collar stays of the type described which are simple and durable, which are effective for their intended purposes and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

On the accompanying drawings forming a material part of this disclosure:

Fig. 1 is a partial elevational view of a man's shirt provided with collar stays constructed in accordance with the present invention.

Fig. 2 is a perspective view of the collar stay per se.

Fig. 3 is an enlarged transverse sectional view taken on the line 3—3 of Fig. 2.

Fig. 4 is a view similar to Fig. 2, but illustrating a modification of the present invention.

Fig. 5 is another view similar to Fig. 2, but illustrating a still further modification of the present invention.

Fig. 6 is an enlarged partial transverse sectional view taken on the line 6—6 of Fig. 5.

2

Fig. 7 is still another view similar to Fig. 2 illustrating another modification of the present invention.

Fig. 8 is an enlarged partial transverse sectional view taken on the line 8—8 of Fig. 7.

Fig. 9 is a perspective view of a collar stay constructed in accordance with a still further modification of the present invention.

The collar stays, as disclosed in connection with the first form of the present invention illustrated in Figs. 1 to 3, are to be mounted on the wings 10 of a conventional soft collar 11 attached to a man's shirt 12, see Fig. 1.

The stays are provided in pairs to have a right-hand stay and a left-hand stay and each includes a body 20 of any desired light weight material. The bodies 20 are triangular in shape to conform to the triangular formation of the wings 10 of the collar 11. The bodies 20 are further characterized by long legs 21 for extension along the depending end edges of the wings 10 and shorter legs 22 for extension along the junction of the wings of the collar 11 with the neck band of the collar. The ends of the legs 21 and 22 of the bodies are connected by the usual hypotenuse sides 23. In this first form of the invention, the centers of the bodies are formed with triangular cutouts 24 for reducing the bulk of the bodies 20.

As best shown in Fig. 2, the bodies 20 are given a slight preset curvature from top to bottom so as to be arcuate in side elevation from top to bottom. The bodies are mounted on the wings 10 to be hidden from view and with their convex sides facing outward so as to hold the wings 10 in a slight forwardly curved position with the tip ends of the wings 10 directed rearward. The slight curvature imparted to the wings 10 by the bodies 20 gives the wings a pleasant rounded appearance and retains the tips from curling forward and upward while the shirt 12 is being worn.

The manner of mounting the bodies 20 upon the wings 10 of the collar 11 forms no part of the present invention, which is concerned entirely with the formation of the stays per se. However, it is appreciated that the stays could be removably inserted into pockets, not shown, secured to the inner faces of the wings 10. On the other hand, if desired, the stays could be sewn in position between layers of the collar 11 at the time that the collar is being assembled or stitched, cemented or secured in any other desired manner to the inner faces of the wings 10 of the collar 11.

As previously indicated, the bodies 20 are preferably formed of a light weight material, which might be a non-corrosive metal. However, it is preferred to form the bodies of one of the inert synthetic resinous materials, particularly in those instances where the stays are incorporated as a part of the collar 11, making it possible to launder the shirt without harmful ef-

fects from the material of the stays. In such instances, the resinous materials used should be one of the thermosetting resinous materials so that the hot water used to launder the shirt will not effect the preset curvature of the stays.

The modification of the invention shown in Fig. 4, is characterized by the fact that the body 20' is constructed to be one piece of material without cutout as in the previous form of the invention.

In all other respects, the form of the invention shown in Fig. 4 is similar to that previously described and like reference numerals are used throughout to identify like parts.

Figs. 5 and 6 illustrate another modification of the invention, in which the body 20 forming the stay is reinforced so as to more rigidly maintain its preset curvature.

Reinforcement of the body 20 is accomplished by forming a bead 25 along the inner edge of the leg 21' of the body which defines the respective side of the cutout 24. The bead 25 extends substantially the full length of the inner edge of the leg 21' and stiffens the body parallel with its normal curvature.

The modification of the invention shown in Figs. 5 and 6 is also in all other respects similar to that described in connection with Figs. 1 to 3 and like reference numerals are used to identify like parts.

Referring now to the further modification of the invention shown in Figs. 7 to 8, there is illustrated still another means for reinforcing the normal curvature of the body 20. This reinforcement is also characterized by a bead 26 formed along the inner edge of the short leg 21'' of the body which defines the adjacent side of the cutout 24. Molded into the material of the bead 26, there is a corresponding length of curved semi-rigid wire 27. The wire 27 should be rigid enough to maintain the desired preset curvature, but should not be so rigid as to make the body 20 completely non-flexible. The wire 27 is preset to the curvature of the body 20 and functions in conjunction with the bead 26 to maintain the desired curvature of the body.

Again, the form of the invention shown in Figs. 7 and 8 is similar to that described in connection with Figs. 1 to 3 and like reference numerals are used throughout to identify like parts.

In the modification of the invention shown in Fig. 9, the collar stay is characterized by an elongated light weight body 20''' having a slight preset longitudinal curvature to be arcuate from one end to the other. The body 20''', as in the previous forms of the invention, is to be mounted along the depending end edge of the wing of a collar with its convex side faced outward to hold the wing in a slight outward curvature with the tip end of the wing directed inward. The bodies 20''' can be attached to the wings of the collar as described in connection with the previous forms of the invention and will, of course, be provided in pairs one for each of the wings of the collar.

From the foregoing description, it is apparent that the present invention proposes novel relatively simple collar stays which when mounted in position on the wings of a conventional soft collar will impart a pleasing rounded configuration to those wings and at the same time retain the tips of the wings from turning forward and upward detracting from the neat appearance of the shirt collar and becoming an annoying bother to the wearer of the shirt.

It is to be understood that these collar stays

may be used in all types of garments of men, women and children in which the collar requires shaping and reinforcement.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. Stays for the wings of a soft collar, comprising a light weight body for each of the wings, said bodies being shaped to conform to the shape of the wings and mounted thereon to be hidden from view when the collar is worn, said bodies being preset to a desired curvature from top to bottom and mounted on the wings with their convexed sides faced outward causing the wings to assume a rolled position retaining the tip ends of the wings from curling forward and upward, said bodies being triangular in formation to have one leg for extension along the dependent edges of the wings and one leg for location in the junctions of the wings with the neck-band of the collar, said bodies having triangular cutouts reducing the bulk of the bodies, and a reinforcing bead formed along the inner edge of the first-named leg of said body defining the respective side of said cutout to maintain said body in its preset curvature, and a length of wire molded into the material of said bead.

2. Stays for the wings of a soft collar, comprising a light weight body for each of the wings, said bodies being shaped to conform to the shape of the wings and mounted thereon to be hidden from view when the collar is worn, said bodies being preset to a desired curvature from top to bottom and mounted on the wings with their convexed sides faced outward causing the wings to assume a rolled position retaining the tip ends of the wings from curling forward and upward, said bodies being triangular in formation to have one leg for extension along the dependent edges of the wings and one leg for location in the junctions of the wings with the neck-band of the collar, said bodies having triangular cutouts reducing the bulk of the bodies, and a reinforcing bead formed along the inner edge of the first-named leg of said body defining the respective side of said cutout to maintain said body in its preset curvature, and a length of wire molded into the material of said bead, said wire having a preset curvature conforming to the curvature of said body and rigid enough to maintain said preset curvature and yet leave said body free for slight flexing.

ERNEST HEUMAN.
